WINDOW STRUCTURE

Wilbur B. Burke, East Cleveland, Ohio

Application June 26, 1947, Serial No. 757,226

1 Claim. (Cl. 189—72)

1

This invention relates to windows, and more particularly to a construction involving metal, and it is among the features of the invention to provide a construction adaptable to new or old buildings, and in the case of the latter to suitably fit irrespective of distortions as commonly found in window openings in the walls of old buildings. Sash-guide means is provided moreover, which is not too loose nor too tight for proper raising and lowering of the sashes. Other objects and advantages will appear from the following description.

To the accomplishment of the foregoing and related ends, the invention, then, comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings—

Fig. 1 is an inside elevational view of a window embodying the present invention;

Fig. 2 is a section taken on a plane clear of the inside trim and stops, as at line II, Fig. 4, and illustrating how my construction sits into a distorted window opening as of an old building;

Figs. 3, 4 and 5 are enlarged detail sections taken on planes substantially indicated by lines III—III, IV—IV and V—V, Fig. 1;

Figs. 6 and 7 are similarly detail sections taken on planes substantially indicated by lines VI—VI and VII—VII, Fig. 1;

Fig. 8 is an enlarged perspective view showing the assembly of an upper corner of the sash-guide;

Fig. 9 is a fragmentary perspective view showing a mode of attachment of the insert framing in wood supports; and

Figs. 10 and 11 similarly illustrate forms of attachment in brick and block constructions.

In general, the invention provides insert-framing, which in the form of rails 2, 3, Figs. 6 and 5, and stiles 4, 5, Figs. 3 and 4, these being of metal, are attachable in the window opening of the building. In the case of such an opening in a wooden building, the rails and stiles may be secured by screws 7, as indicated in Fig. 9. These rails and stiles are provided with a stop-flange 8 at one edge, e. g. the weather side of the window opening, and by having such stop in the form of a further re-bent margin 9, a recess is provided for the reception of a suitable packing 10. With some resiliency in the packing, as may be

had for instance with packing involving rubber or rubber-like material, with or without fiber reinforce, an adjustability in the seating of the sash-guide G results, and distortion such as found in the window openings of old buildings may be compensated for in the seating of the sash-guide, and a weather-tight joint packing is also assured.

The sash-guide is also of metal, hollow, and may be formed of opposed outer and inner telescoping channels 11, 12, as for the stiles and top rail, and the outer and inner channels 11', 12' for the bottom rail, the overall dimensions being uniform. The inner channels may be of lighter gauge metal than the outer. A peculiarity of the inner channels 12 is that they are provided with grooves 14 which have an arcuate-base 15 and which provide resiliency in the walls of such grooves for receiving tongues or ribs 16 which project along the stiles of the window sashes S. The latter also desirably are of metal, and while they may be of single-glazed character, generally double-glazing is preferred, and for such the sashes may be formed of nested channels 17, 18 having flanges 19, 20 to somewhat resiliently grip the panes of glass, suitable sealing material being interposed between the glass and the metal. If the metallic elements as set forth be made of aluminum, brass, stainless steel or the like, rusting or corrosion can be eliminated, also necessity of painting.

The sash-guide, thus as a rectangular frame to be set into the opening and engage against the packing 10 in the flange of the insert framing, may carry the upper and lower sashes U, L, as a convenient unit. For insertion of the sashes, the sash-guide allows of sufficient disassembly, as illustrated at Fig. 8, the holding screws 25 being arranged to pass through openings in the 40 ends of the stiles and into threaded openings 26 in suitable lugs or cleats 27 carried in the ends of the adjacent rails. Thus, by sufficient spreading of the joint between stiles and rails of the sash-guide, the sashes may be positioned therein and the joints be tightened up. It is noticed that by the provision of projecting ends 29 on the outer channel of the rails, and corresponding cut-outs 30 on the ends of the stiles, an interdigitating form of joint at the corners is attained. At 45 the same time, an opening is left between the end of the rails and the adjacent end of the stiles, whereby ventilation of the hollow sash-guide is secured. As such openings are not externally exposed but are internal, circulation of air and consequent elimination of condensation of moisture

is assured in the hollow structures, access of air from the room being permitted by the relatively loose fit toward the room side as contrasted with the sealed fit at the packing on the weather side.

The sash-guide may be held in place by stops 30, 31 at the inside. Conveniently, these may be hinged to the insert-framing, and piano-type hinges 32 are particularly desirable. While the sash guide may seat unattached and be thus held by the stops, in most cases it is preferred to secure the sash-guide to the stop at one side, as for instance by welding to the hinge member 33 which also carries the stop 30. Thereby, on swinging the free stop 31 inwardly out of the way, the entire sash-guide with its contained sashes U, L, may be swung inwardly for cleaning, etc.

For securing the sashes, a convenient slide 35, Fig. 7, may be mounted on the lower sash L, and having a projecting flange 36, may seat under the upper sash U, preferably within a protecting narrow sheath 37. Thumb lugs 38 facilitate the moving of the slide 35 into locking or unlocking positions with respect to the sashes, and thumb screws 39 permit tightening of the slide in the desired position.

Of particular importance is the arrangement of the grooves 14 in the sash guide for the receiving of the longitudinal tongues or ribs of the sashes. By reason of the resiliency provided in the construction shown, the sashes slidably fit in the sash-guide draft-tight. Moreover, by proper correlation between thickness of the metal and the proportioning of the arcuate groove base, the walls of the groove 14 may resiliently frictionally grip the sash tongues such as to hold the sash in any position without requirement of counterweights. At the same time, by reason of the resilient engagement, the sashes may be moved up and down without undue effort.

Instead of continuing the sash grooves 14 in recess-form on the lower rail of the sash guide, it is preferred to form the inner channel 12 with the rib or tongue 40, and form the rail of the adjacent sash with a groove 41, whereby a draft-type joint between the lower sash and sash-guide is attained, and without a form of groove subject to being filled up by dirt.

Where the window opening in the wall of the building involves brick blocks or stone, the insert-framing may be provided with out-turned projections or flanges, and as illustrated at Fig. 10, a flange 42 struck up from the insert-framing may position the latter adequately against the adjacent brick or block wall, or as illustrated in Fig. 11, projections 42 may be such as to seat between bricks and thereby hold the inserts.

It is to be emphasized that with ample clearance or spacing between the sash-guide and the frame, as afore-indicated, a compensative fit of the sash-guide is assured irrespective of any distortion in the window frame opening due to settling or sagging of the building. Furthermore, with such space there is an active air circulation between the sash-guide and the framing, the openings at the top and bottom facilitating such circulation; and within the sash-guide itself the hollow space accessible to openings at top and bottom also provides circulation. Thus, with such ample circulation in

and about the sash-guide, condensation of moisture is prevented, and an important problem with metal sashes is solved.

Other modes of applying the principle of the invention may be employed, change being made as regards the detail described, provided the features stated in any of the following claims, or the equivalent of such, be employed.

I therefore particularly point out and distinctly claim as my invention:

In window construction, a sash-guide formed of opposed sheet metal channel members secured together, in combination with a means for eliminating sash-counterweights which comprises a transversely-flat web in the inner one of said channel members and a pair of guide grooves formed in it characterized by cross-section in substantially complete circle form with a narrow interruption providing margins in opposition to each other in resilient compression, means for engaging the transversely-flat periphery surfaces of the stiles of window sashes and for laterally reinforcing said groove margins, embodying the integral portion of said inner channel member web connecting the grooves and the integral portions of the web laterally of the grooves, and window sashes having longitudinal tongues sliding in such grooves.

WILBUR B. BURKE.
